UNITED STATES PATENT OFFICE.

SAMUEL T. THOMAS, OF LAWRENCE, MASSACHUSETTS.

LOOM.

Specification of Letters Patent No. 13,186, dated July 3, 1855.

To all whom it may concern:

Be it known that I, SAMUEL T. THOMAS, of Lawrence, in the county of Essex and State of Massachusetts, have invented an 5 Improved Loom for Weaving Fancy Fabrics; and I do hereby declare that the same is fully described and represented in the following specification and the accompanying drawings, letters, figures, and references 10 thereof.

Of the said drawings, Figure 1, denotes a top view of my said loom; Fig. 2, is a front elevation of it. Fig. 3, is an elevation of the right end of it. Fig. 4, is a vertical and 15 longitudinal section of it, the same being taken through the cam shaft to be herein-after described; Fig. 5, is a vertical central and transverse section of it; Fig. 6, is an elevation of the left end; such other figures as 20 may be necessary to a full and complete delineation of the parts constituting my invention will be hereinafter referred to and described.

In the said drawings A, exhibits the frame 25 of the loom, it being constructed in any proper manner to support the operative parts to be hereinafter explained.

B, is the main driving shaft; C, the cam shaft; D, the lay; E, the breast beam; F, the 30 yarn beam; G, the reed, and H, H, H, a series of harnesses, such being the component or principal parts of an ordinary fancy loom. The main driving shaft gives motion 35 to the cam shaft by means of gears a, b, affixed respectively to them as seen in Fig. 6.

The two harnesses which are nearest to the lay are for the purpose of producing what is termed plain weaving, while with the remainder fancy weaving is effected. 40

The top bar of each fancy weaving harness is supported by two cords c, c, which extend upward against and turn horizontally over friction pulleys or sheaves f, f, arranged as seen in the drawings, the said two cords being hooked to a strap g, which is fastened to the upper end of one of a set of upright triarmed levers I, I, I. The lower bar of each of said harnesses is attached to two cords h, h, which work downward around, 45 and are carried horizontally under two friction pulleys i, i, arranged as seen in Fig. 4. From thence both of these cords are united to one strap k, attached to the lower end or arm of the triarmed lever I, to which the upper bar of said harness is connected as hereinbefore mentioned. Each of the levers I, is

arranged so as to turn on a common fulcrum or horizontal shaft K, and has a third arm l, extended from it and provided with a stud or friction roller, which is made to enter and work in a groove of a series of cams, L, L, L. These cams are arranged and fixed upon a horizontal shaft M, as seen in Figs. 1, 2, 3 and 4. By means of bevel gears n, and o, the said shaft receives motion from a horizontal shaft (represented at m, in Fig. 1, by dotted lines) on which is a spur gear w, that is made to engage with a pinion p fixed upon one end of the driving shaft B. During the rotary movement of the driving 70 shaft rotary motion therefrom will be communicated to the cam shaft M and its cams, and so as to produce such movements of the several triarm levers I, I, I, as may be necessary to produce the necessary vertical 75 movements of their harnesses in the order which may be required.

By supporting and operating, in the above described manner, those harnesses which are used for fancy weaving, we are not only enabled to cause each harness to play only in a vertical plane, but we arrange its operative mechanism in such a position as will enable us to gain much easier access thereto than would be the case were it placed underneath 85 the harnesses and within the main body of the loom frame in the usual way.

It will readily be seen that when a harness is suspended from the end of a horizontal lever, in consequence of its point of suspension being made to work in the arc of a circle, such harness notwithstanding it may have a vertical movement will at the same time have more or less of lateral movement, which will operate not only to produce wear 95 of the warp, but also of the eyes or loops of the harness. It will therefore be seen how desirable it is that a harness should play vertically without having any lateral motion whatever imparted to it and whether 100 such be in directions transversely or longitudinally of the loom. Besides the peculiar lateral movement of the harness as occasioned by a lever as above set forth, it is also desirable to prevent the harness from having 105 any swaying lateral movement such as generally occurs when its bars are connected to levers in the ordinary way.

By attaching each bar of each harness to two cords and running such cords over pulleys and fastening them to a lever as hereinbefore explained, such lever when put in op-

eration will cause such harness to be moved vertically and without either any lateral or swinging motion.

The two front harnesses which are for the purpose of weaving plain cloth or selvages or plain stripes in the fancy weaving have their upper bars operated by cords q , q , which work around four pulleys, s , s , and, t , t , arranged as seen in Fig. 1. Each cord 10 after being attached to one end of one of the bars is carried upward and partially around one of the pulleys, s , and is next made to pass horizontally toward the farthest pulley, t , and is carried into the groove of said 15 pulley and downward and is fastened to the opposite end of the other harness bar. In this way both harness bars are not only supported by pulleys, but each end of one is connected with the opposite end of the 20 other by a cord. The lower bars of these harnesses are respectively attached by means of four cords u , u , to four straps v , v , each of which is attached to and extended around the periphery of a pulley or drum, 25 w , or, x , fixed upon a horizontal shaft o , as seen in the drawings. The two straps under each two adjacent ends of the harnesses are carried in opposite directions around their drum as seen in Fig. 5, in order that when 30 the shaft is rotated in one direction it will wind up two of the straps and unwind the other two, the same causing one of the harnesses to descend and the other simultaneously to ascend. The rotary movement of 35 the shaft, O , is produced by means of a sectoral lever, P , (see Fig. 3) which works upon a fulcrum at, y , and is connected to the shaft by means of two straps or bands, z , z , which are attached to and wound in opposite directions around the periphery of a 40 small drum or pulley a' , fixed upon the shaft, O . On one side of the lever, P , is a stud or roller b' , which is represented in Fig. 3, by dotted lines the same being made 45 to enter the groove of a cam Q , fixed upon the cam shaft C . During the rotation of the shaft, C , a reciprocating vertical movement will be imparted to the lever, P , so as to produce through the action of the straps, 50 z , z , a reciprocating rotary movement of the shaft, O .

Upon the cam shaft, C , there is placed a cylindrical grooved cam, R , the groove of which is represented in Fig. 7, as developed on a 55 plain surface. A friction roller or stud projecting upward from one end of a horizontal lever, S , enters and works in the groove of said cam, said lever playing upon a fulcrum at, T , and having its front end fixed to one 60 end of a flexible strap, U , whose opposite end is fastened to the picker staff, V , such picker staff extending up into and working in the shuttle box W .

The strap, U , should be sufficiently stiff 65 to force the picker staff backward immedi-

ately after each throw of the shuttle and while the lever, S , is moving in a direction toward the staff. By having the strap made with such a degree of stiffness we avoid the necessity of applying a spring to the picker 70 staff, for the purpose of retracting, and we cause the strap to perform the function not only of drawing the picker staff but that of forcing it backward. This is a very important improvement in operating the picker 75 staff, for although it has heretofore been drawn in one direction only by a strap, such strap has always been made so flexible as to require some other contrivance for the retraction of the lever. It is well known that 80 such retractive mechanism as has been generally employed has been very liable to become deranged or get out of order on account of the nature of its construction and the blows, which the picker staff is 85 constantly receiving during its operation. The stiff strap working in two directions and having flexibility or elasticity sufficient to relieve the picker staff from the sudden blows it receives has been found to operate 90 with great success, advantage, and economy.

In Figs. 1, and 5, there is shown a lever, X , of the stop motion or mechanism by which the movements of the loom are arrested whenever breakage of the filling 95 thread occurs. This lever, or its upper arm, as is well known has a reciprocating movement given to it, and usually has been operated in connection with a forked lever, Y , whose rear or horizontal arm carried a small 100 hook which by the peculiar movement of the lever was maintained out of the path of motion of the lever X , while the filling thread remained whole or unbroken. Whenever breakage of the filling thread took place the 105 hook would be dropped into the path of the lever and upon the upper arm of said lever in such manner as would cause the hook and its supporting frame to be moved backward by the lever and so as to give motion to another lever which acting against the shipper would throw it from its notch and thereby 110 produce a stoppage of the loom, said operation being understood by weavers.

In my improved loom I apply the forked lever, Y , to a stationary arm or projection c' , fastened to the breast beam, E , and I joint to the upper arm of the lever X , a small lever or pitman d' , as seen in Figs. 1, 115 and 6, and also in Fig. 8, which is a vertical section of said pitman, and that part of the lever X to which it is attached. The 120 said pitman d' , turns upon a fulcrum, e' , and operates in connection with a small rocker lever, f' , which works in the lever X , and is composed of a shaft and two arms g' h' , as seen in side view in Fig. 9.—One 125 of these arms, viz. h' rests and works against an inclined plane or cam i' , formed on the underside of the rear or gravitating arm of 130

the lever or pitman d' , the other arm, g' , extending upward from the lever and so that when the catch hook of the lever Y falls downward it may come into the path 5 of movement of said arm and thereby catch upon said arm so as to cause the rocker lever, f' , to be rotated in such manner as to produce the depression of the front arm of the pitman d' . When such arm is so de- 10 pressed and moved forward it will be carried into contact with the lever k' , of the shipper l' , and will move said lever so as to force said shipper off the shoulder or notch m' , of its slotted guide plate n' . The helical spring, o , is fixed to the rocker lever, f' , and the lever X , and operates so as to re- 15 tract the lever, f' , when the lever, X , moves backward. The gravitating arm of the pitman when relieved of the pressure of the lever f' will fall and raise the front arm of the pitman entirely above the lever, k' , by which the shipper is actuated. 20

From the above it will be seen, that the only strain there is produced upon the catch 25 hook of the forked lever Y , is that which is just sufficient to move the rocker arm, f' , and the pitman so that the latter may be moved by the lever, X , against the lever, k' . Thus the great strain necessary to effect the 30 movement of the lever, k' , is not borne in my improved "stop motion" by the forked lever Y , as it is in various other "stop motions."

In Fig. 1, the yarn beam, F , is represented as furnished with a friction pulley, p' , which has a band or cord r' wound several times around its periphery. One end of this cord is fastened to a projection from the lower part of a lever, s' , which 35 turns upon a fulcrum at its upper end, and is suspended therefrom, and between the pulley and its end of the main frame of the machine. Such lever being particularly exhibited in Fig. 5, which shows by dotted 40 lines that part of it which is in rear of the friction pulley. The other end of the friction cord is attached to a pin or screw bolt t' , which passes and slides through an ear u' , extended from the lever, s' . Below this 45 ear and on the screw bolt there is placed a helical spring, v' , which by means of a screw nut, w' , is borne against the ear u' , and serves to draw the friction cord close to the periphery of the friction roller. In 50 proportion as the cord is drawn tighter upon the periphery of the friction roller so will the tension on the warp be increased. The lever, s' , before named rests against a

spring x' , which is supported in a box or case, y' , fastened to the end of the main frame, as seen in Fig. 5. The said spring, x' , by the tension or draft on the warps caused either by the beat of the lay or the springing of the harnesses will enable the 55 yarn beam to turn a little and accommodate itself to such strain or draft and maintain an equality of tension upon the warp. The friction cord and pulley, while they enable the yarn beam to turn and give out 60 yarn as fast as may be necessary during the weaving process, operate to hold the warp under the blows of the reed. Contrivances for such purpose are common in other looms—although differing in construction and operation from that hereinbefore de- 65 scribed.

I claim—

1. The improvement of working the picker staff in opposite directions by means of a flexible strap having sufficient stiffness to 80 move said picker staff backward, when said strap is moved by a lever substantially as specified.

2. I also claim combining with the operating lever X , and, the forked lever, y , of 85 the stop motion, a lever or pitman, d' , and a tripping or rocker lever, f' , or the equivalent thereof, the same being for the purpose of operating the lever of the shipper and relieving the forked lever, Y , of strain as 90 specified, the said improvement enabling to be used, a forked lever, Y , of great lightness and delicacy of construction, and capable of being operated by the finest qualities 95 of weft and thread.

3. I do not claim applying a friction pulley and band to the yarn beam, nor do I claim sustaining the warp by means of a guide roller supported by upright levers operating with weighted levers by two sectors 100 and gears and for the purpose of maintaining an equality of tension on the warp during the weaving operation, but what I do claim is arranging and combining the friction pulley, p' , the band, r' , the lever, s' , and spring, 105 x' , of its equivalent, so as to operate together and with respect to the yarn beam substantially as specified.

In testimony whereof, I have hereunto set my signature this seventh day of April, 110 A. D. 1855.

SAMUEL T. THOMAS.
